US00D962877S

(12) **United States Design Patent** (10) **Patent No.:** **US D962,877 S**
Dratsch et al. (45) **Date of Patent:** **** Sep. 6, 2022**

- (54) **TOGGLE SWITCH WITH VARIABLE ACTUATOR CONTROL**
- (71) Applicant: **Pass & Seymour, Inc.**, Syracuse, NY (US)
- (72) Inventors: **Oleg Dratsch**, Manlius, NY (US); **Patrick J. Murphy**, Marcellus, NY (US); **Alec J. Brindisi**, Syracuse, NY (US); **Theodore P. Junko**, Manlius, NY (US)
- (73) Assignee: **Pass & Seymour, Inc.**, Syracuse, NY (US)
- (**) Term: **15 Years**
- (21) Appl. No.: **29/714,879**
- (22) Filed: **Nov. 26, 2019**
- (51) LOC (13) Cl. **13-03**
- (52) U.S. Cl. **USPC D13/169; D13/170**
- (58) **Field of Classification Search**

(57) **CLAIM**

The ornamental design for a toggle switch with variable actuator control, as shown and described.

DESCRIPTION

FIG. 1 is a first isometric view illustrating the toggle switch with variable actuator control;

FIG. 2 is a front plan view thereof;

FIG. 3 is a rear plan view thereof;

FIG. 4 is a left side view thereof;

FIG. 5 is a right side view thereof;

FIG. 6 is a top side view thereof;

FIG. 7 is a bottom side view thereof; and,

FIG. 8 is a second isometric view thereof.

The broken lines depict portions of the toggle switch with variable actuator control and form no part of the claimed design.

1 Claim, 8 Drawing Sheets
